NASH CHEEK, OF CHAPEL HILL, NORTH CAROLINA.

Letters Patent No. 80,599, dated August 4, 1868; antedated July 30, 1868.

IMPROVEMENT IN BURGLAR-ALARM LOCKS.

The Schedule referred to in these Letters Patent and making part of the same.

TO ALL WHOM IT MAY CONCERN:

Be it known that I, NASH CHEEK, of Chapel Hill, in the county of Orange, and State of North Carolina, have invented a new and improved Alarm-Lock; and that the following description, taken in connection with the accompanying drawing, hereinafter referred to, forms a full and exact specification of the same, wherein I have set forth the nature and principles of my said improvements, by which my invention may be distinguished from all others of a similar class, together with such parts as I claim, and desire to have secured to me by Letters Patent.

This invention relates to a lock, of simple construction, which is designed to be unpickable, and capable of being applied in all cases where an ordinary lock may be used, and in combining with said lock an alarm, all arranged as hereinafter fully shown and described.

The accompanying drawing represents an internal view of my improved lock, with the alarm attached.

A represents the case of the lock, which may be of the usual rectangular form, and B is the bolt, fitted within the case in suitable guides, and having a spring, C, bearing against its upper edge, which spring has a tendency, when the bolt is shoved outward, to keep a notch, α , in the lower edge of the bolt, on the lower part of the back guide b of the bolt, so as to involve the necessity of raising the back part of the bolt before it can be shoved back.

In the back part of the bolt B there is a hole, c , which, when the bolt is shoved forward and the lock locked, receives a pin, d , at the end of a spring, D, which is secured within the case A. The elasticity of the spring D keeps the pin d in the hole c of the bolt B, and said pin consequently must be removed from or shoved out of the hole c before the bolt can be shoved back.

This result is effected by the bit of the key, which, as it is turned in the lock, presses upon the spring D, and throws its pin d out from the hole in the bolt just previous to the bit entering a notch, e , in the bolt, by which the inner end of the bolt is raised free from the rear guide b , and the bolt thrown back and the lock unlocked.

In the lock-case A there is a circular chamber, E, in which the bit of the key works, and there is also within the lock-case a lever, F $\times$, having its fulcrum at f , and its lower end connected by a link, g, with a lever, h, whose lower end is pivoted to the bar i, which passes through an opening in the lock-case.

E represents the door or shutter to which the lock is applied, and F is a sliding bar attached thereto, and having a lever, G, connected to its upper end by a pivot, j, the fulcrum of said lever being at a^x .

On one end of this lever a spring, k, bears, and the opposite end is provided with a tooth, l, which catches into a toothed wheel, H, the shaft I of which has a cord, J, attached, with a weight, K, at its lower end.

This shaft I has a drum, L, upon it, provided with radial teeth m, which, when the shaft is rotated, come in contact with an arm, L', on a shaft, M, to which a bell-hammer, N, is attached. The shaft M has a spring, O, connected to it, which spring has a tendency to throw the hammer in contact with the bell P, the hammer being thrown back from the bell by the action of the teeth m against the arm L' of the shaft M.

The tooth l of lever G serves to retain the wheel H, and prevent the weight K from rotating it when the cord J is wound upon the shaft I.

The bar F has a pin, n, projecting from it, and Q is a gun or pistol attached to the shutter or door, in such a position that the pin n will be in front of its trigger o when the lock is locked, and the bar F is held upward by a notch, p, in its lower end, receiving a pin, q, in the shutter or door, as shown in the drawing.

The operation is as follows: When the lock is in a locked state, the pin q in the recess or notch p in the bar F, and the cord J wound upon the shaft I, the alarm is set, and it will be seen that when the bolt B is shoved back, and the lock unlocked, a lip, b $\times$, on the bolt will strike lever F $\times$, and the bar i will be moved, and strike the bar F and throw it off or free from the pin q, and the spring k will then, by its pressure on lever G, throw down the bar F and raise the tooth l from the wheel H. The weight K will then, of course, rotate the shaft I, and the bell P will be sounded. The gun or pistol Q will also be fired, in consequence of the pin n striking the trigger o when the bar F is forced down.

In addition to these alarms, an ordinary bell, R, provided with a clapper, r, may be attached to the end of the shaft M. The shaft M is provided with an arm, s, to come in contact with a pin or stop, t, in the shutter or door E.

Only one or all of these alarms may be used, as desired.

In order to prevent the insertion of a key into the lock from the outer side of the door, a slide-plate, S, may be placed within the lock, and operated by a lever, T.

This slide-plate is not new, however, and may be seen in various locks.

Having thus described my invention, I claim as new, and desire to secure by Letters Patent—

1. The lever F^X, connected with the bar i, as shown, in combination with the sliding bar F at the outer side of the lock, and attached to the shutter or door, and arranged so as to operate an alarm, substantially as shown and described.

2. The lever G, pivoted to the bar F, in connection with the spring k, toothed wheel H, cord J, and weight K or an equivalent, arms m on the drum of the shaft I, shaft M with arm L' and bell-hammer N attached, spring O and bell P, all arranged and combined to operate in connection with the lock, substantially as set forth.

NASH CHEEK.
